CLAIM

We claim the ornamental design for a mobile computing device, as shown and described.

DESCRIPTION

FIG. 1 is a first perspective view of an example mobile computing device;
FIG. 2 is a second perspective view thereof;
FIG. 3 is a front view thereof;
FIG. 4 is a back view thereof;
FIG. 5 is a first side view thereof;
FIG. 6 is a second side view thereof;
FIG. 7 is a top view thereof; and,
FIG. 8 is a bottom view thereof.
